UNITED STATES PATENT OFFICE

2,538,061

FRICITION DRIVE FOR HOISTING APPARATUS

Julius Torok, Allentown, Pa.; Anna Torok executrix of said Julius Torok, deceased

Application August 28, 1946, Serial No. 693,427

5 Claims. (Cl. 64—30)

1

This invention relates to hoisting apparatus and more particularly to apparatus of the type employed for operating a grab bucket or the like in which the raising and lowering operations, as well as the opening and closing of the bucket, are effected by two separate lines. With such apparatus it is at times required that the lines be moved in unison and at the same speed so that neither line acquires any slack, and at other times it is necessary to effect a differential movement between such lines to open or close the bucket.

To accomplish the required movements it has been proposed to operate the lines controlling the bucket by two separate drums, one being a load drum and the other being a holding drum, each operated by a separate motor; or by the same motor through a complicated and costly differential mechanism with brakes applied to each drum. Alternatively a single hoisting drum and motor may be used in association with a load line, and a second motor may be mounted on the bucket to open and close it; or differential drum hoists may be employed in which the drum diameter varies, the latter system being useful for lifts of fixed distances only; or a single mechanically operated load line may be applied to the bucket for raising and lowering the same with its opening or closing accomplished by hand operation.

The principal object of the present invention is to provide a hoisting apparatus which is relatively simple in design, economical to manufacture, and requires less maintenance and is otherwise free of the difficulties encountered with the various systems which have heretofore been proposed as mentioned above.

A further object of the invention is to render it practicable to utilize a combination involving one motor and two separate drums frictionally connected to each other by provision of means for controlling the frictional connection between such drums which is mechanically dependable and may be relied upon to produce a constant force of the desired magnitude to insure proper operation. Additionally provision is made for regulating the degree of friction between such drums, whenever it may become expedient to do so.

Another object of the invention is to provide a brake mechanism for the frictionally connected drums of such character that the load drum is automatically held against rotation when the motor for operating it is shut off and the holding drum is subject to a braking pressure applied according to the will of the operator.

Other objects and advantages of the invention

2

will become more apparent from the description of a practical embodiment thereof which is hereinafter set forth having reference to the accompanying drawings, whereof:

5 Fig. 1 represents a side elevation of hoisting apparatus of this invention as applied to a grab bucket which is moved from one location to another by means of an overhead trolley;

10 Fig. 2 is an end elevation of said hoisting apparatus, as viewed from the left of Fig. 1, showing details of the braking mechanism by which the operator controls the holding drum of the hoist;

15 Fig. 3 is an enlarged plan view of the hoisting apparatus and portions of the trolley upon which it is mounted;

20 Fig. 4 is a vertical cross section of the same taken as indicated by the arrows IV—IV of Fig. 3;

Fig. 5 is a further enlarged vertical cross section, similar to Fig. 4, showing the spring retainer at the end of the holding drum of the hoist and various parts associated therewith;

25 Fig. 6 is a vertical cross section at the spring retainer taken as indicated by the arrows VI—VI of Fig. 5; and

Fig. 7 is a fragmentary section of a portion of the holding drum and spring retainer, taken as indicated by the arrows VII—VII of Fig. 6.

30 Fig. 8 is a perspective view of one of the bushings by which the holding drum is freely mounted upon its central shaft.

As shown in Fig. 1 the hoisting apparatus of this invention is illustrated in connection with a grab bucket B of conventional design having a fixed upper head 1 and a movable lower head 2.

35 In a manner well known to those skilled in the art the grab bucket is operated by means of a holding line 3 which is attached to the fixed head 1 and which serves to sustain the weight of the bucket while it is open and by a load line 5 which is connected to the lower head 2 and which serves as a hoisting or closing line. The lower head 2 is so connected to the jaws 4 of the bucket B and to the load line 5 that when the bucket is suspended by the holding line 3 and the load line

40 5 slacks off the jaws 4 will open, and when the load line 5 is pulled taut the jaws 4 will close. With buckets of this type the opening and closing operations require a differential movement of the holding line and load line, and during

45 50 raising or lowering of the bucket it is desirable that the two lines be caused to move in unison at the same speed so that neither line can acquire any slack.

As shown in detail in Fig. 3 the hoisting apparatus includes an electric hoisting motor 13

3

which is reversible and drives a shaft 11. A solenoid brake 12 is associated with shaft 11 and is so controlled that whenever the motor 13 is shut off the brake is automatically operative to hold shaft 11 against rotation, and whenever the motor 13 is caused to run the brake is released. Such a solenoid brake and the circuits for controlling it are well known, and hence the electrical details thereof are not illustrated herein, and these parts are shown conventionally in dot-and-dash lines. Shaft 11 drives the main load drum 21 through a reducing gear train consisting of gears and pinions 7, 8, 9, 10. Gear 7 is bolted directly to the drum 21 on which the load line 5 is wound, and the load drum 21 is securely fixed to shaft 16 so that it is positively driven by motor 13 and incapable of axial movement relative to the shaft 16.

The holding line drum 22 is driven by the load drum 21 through a frictional connection consisting of an annular disk 6, see Fig. 4, of brake lining or similar material which is interposed between the end faces of the contiguous drums 21 and 22 and protected by the flange 24 of drum 21. Formed integrally with the holding drum 22 is a cylindrical surface 25 engaged by a brake mechanism 26, see Figs. 1 and 2. Whereas, the load drum 21 is fixed on shaft 16 and positively driven thereby, the holding drum 22 is free to rotate upon shaft 16 and to facilitate this bushings 17 are provided.

The holding drum 22 is slightly larger in diameter than the load drum 21. At one end it is provided with a telescopic cylindrical housing 30, shown most clearly in Figs. 4 and 5, which consists of a cylindrical guard 40, a collar 41 and the end portion of the holding drum 22, and which contains therein six spiral springs 31 which serve to force the holding drum 22 towards the load drum 21. The spiral springs 31 have their axes disposed in a circle about shaft 16, as shown in Fig. 6, and are each accommodated in cylindrical recesses 32 formed longitudinally in a spring retainer 60 and in the end portion of the load drum 22 and confined to axial movement by rigid torque elements in the form of pins 33. Inter-spaced between the six springs 31 are two guide rods 35, shown most clearly in Fig. 7, which prevent the spring retainer 60 from rotating relative to the holding drum 22 while permitting relative axial movement between these elements. By means of a bushing 19 the spring retainer 60 rotates freely upon the shaft 16. The holding drum 22, the housing 30 and spring retainer 60 are drilled and fitted with suitable lubricating fittings 27 which connect with radial passages 28, 28a and 28b leading to the bushings 17, 19.

As shown in Fig. 8, each bushing 17 is provided with a number of holes 24 and is internally grooved at 25 permitting lubricant admitted through passages 28, 28a to be distributed throughout the length of the bushing and to pass from the interior surfaces to the exterior surfaces and vice versa so that all portions of the bushing are lubricated and the holding drum 22 will turn freely with respect to the shaft 16. It may be assumed that the bushing 19 of the spring retainer 60, though somewhat differently shaped, is similarly lubricated.

The cylindrical guard 40 bolted to the collar 41 on shaft 16 bridges the space between the end portion of holding drum 22 and spring retainer 60 and prevents the entry of dust or other foreign matter into this space. Between spring retainer 60 and collar 41 a thrust bearing 15 is provided.

4

The end of shaft 16 in the vicinity of the collar 41 is reduced and threaded as indicated at 42 and is engaged by an adjusting nut 43. A lock nut 44 holds adjusting nut 43 in place. By manipulation of the adjusting nut 43 the compression of springs 31 may be varied and hence the pressure of the holding drum 22 against the friction disk 6 may be regulated.

As shown in Figs. 1 and 2 the brake mechanism 26 comprises a brake band 46 which is tightened by downward movement of brake rod 47 operating through crank arms 48 affixed to a shaft 49. At its lower end brake rod 47 is adjustably connected to an arm 50 on a shaft 51. An additional arm 52 on shaft 51 is provided with a brake pedal 53 at the bottom of the operators cab 54. In an obvious manner the operator can at all times control the degree of pressure applied through mechanism 26 to the holding drum 22.

20 The hoisting apparatus herein illustrated is mounted on a trolley 55, outlined in dot-and-dash lines in Fig. 3, having wheels 56 engaging rails 57 suitably supported on beams 58. By means of a trolley motor 59, the apparatus may 25 be moved back and forth along the rails 57. The trolley 55 is of a conventional design and forms no part of the present invention.

Inasmuch as holding drum 22 has a slightly larger diameter than the load drum 21, there is 30 a tendency for the holding line 3 to be taken up faster than the load line 5 when the bucket B is being raised. However, because of the light pressure exerted between the holding drum 22 and the friction disk 6 a slight slipping occurs 35 but this pressure is nevertheless sufficient to keep the slack out of the holding line 3. The degree of friction between the two drums 21 and 22 should be constant and carefully regulated. Regulation is accompanied by means of adjusting nut 43. The construction and arrangement of the 40 springs 31, within which are partially housed within the spring retainer 60 and partially housed within the end of the holding drum 22, is such as to provide for the application of a constant force 45 of the correct magnitude to insure tension on the holding line 3 when the motor 13 is running and no braking pressure is applied to holding drum 22.

The operation of the hoisting apparatus is as follows: Upon the assumption that the bucket B 50 is loaded and that it is being raised by the hoisting apparatus in order to transfer the load to a point where it is to be discharged, the motor 13 will be running in a direction which will cause the holding line 3 and load line 5 to wind upon the 55 drums to which they are attached. The increased diameter of holding drum 22 will tend to take up the holding line 3 at a faster rate than the load drum 21 takes up the load line 5 but on account of the relatively small amount of friction between 60 the two drums slippage will result and no slack will occur in the holding line. When the bucket B has been raised to the desired height motor 13 is stopped. The solenoid brake 12 then automatically stops shaft 11 and all movement of the 65 load drum 21 ceases. The brake mechanism 26 is then applied by the operator through the medium of brake pedal 53. Both drums are then held against rotation. By means of trolley motor 59 the bucket B may then be moved to a position 70 above the point of discharge. To open the bucket and discharge its contents motor 13 is operated in a reverse direction, and brake pressure is applied at the holding drum 22. Under these conditions slippage occurs at the frictional connection 6. 75 The load line 5 is payed out but the holding line

3 is held against movement and supports the weight of the bucket. Accordingly the jaws 4 open and the load is discharged.

At this point the operator stops motor 13 and releases braking mechanism 26. The holding drum 22 is caused to rotate by the weight of the bucket, the friction disk 6 being insufficient to hold it, and the load drum is held stationary by the solenoid brake 12. The resulting differential movement of lines 3 and 5 closes the bucket. By means of the trolley motor 59 the bucket B is then returned to its original location and lowered by reenergizing motor 13. The holding drum 22 being larger in diameter than the load drum 21 will tend to pay out holding line 3 faster than load line 5, and to prevent this the operator applies a slight pressure at foot pedal 53 sufficient to slow down holding drum 22 to the point where both lines are kept taut but insufficient to stop the movement of the holding drum. When the bucket has almost reached the loading point the operator increases the pressure of brake mechanism 26 causing the load line 5 to be payed out faster than the other line so that the bucket opens and drops onto the pile of material to be conveyed.

To load and raise the bucket the operator then releases brake mechanism 26 and reverses motor 13. The load drum winds up the load line 5 and the jaws 4 automatically close upon the material. Again the operator applies a slight braking pressure upon the holding drum so that the two lines pull in unison as the bucket is raised. The cycle is now ready to be repeated.

It will be apparent that the hoisting apparatus thus described requires only a single motor for its operation and is relatively simple to manufacture as compared with apparatus involving separately operated drums or complicated differential mechanism, and at the same time the apparatus of this invention can be readily controlled by simple movements on the part of the operator. The ease of operation is in large measure due to the fact that the braking of the load drum is effected automatically and that the friction springs 31 are so arranged and incorporated within the structure as to produce the desired degree of friction between the drums, this friction being constant in its application because movement of the holding drum and spring retainer is limited in one direction by the load drum 21, which is fixed on the shaft 16, and in the other direction by the thrust bearing 15, and proper regulation of the pressure at the frictional connection between the drums may be effected by means of adjusting nut 43 and its lock nut 44.

While I have described one example of the invention by reference to a specific embodiment thereof it will be apparent that various changes may be made in the apparatus herein described and illustrated without departing from the spirit of the invention as defined in the accompanying drawings.

Having thus described my invention, I claim:

1. In a hoisting apparatus, the combination with a power-driven shaft of two contiguous drums, one of said drums being fixed on said shaft and positively driven thereby and the other drum being free to rotate upon said shaft and having a frictional connection with said fixed drum, a thrust bearing on said shaft, a spring retainer connected to said free drum and engaging said thrust bearing, guide rods for connecting said spring retainer to said free drum whereby said retainer rotates with the free drum while

having capacity for relative axial movement with respect thereto, a telescopic housing for said retainer and thrust bearing, and a series of coil springs disposed within said telescopic housing and between said retainer and free drum, said springs having their axes disposed in a circle about said shaft for urging the free drum towards the fixed drum.

2. In a hoisting apparatus, the combination with a power-driven shaft of two contiguous drums, one of said drums being fixed on said shaft and positively driven thereby and the other drum being free to rotate upon said shaft and having a frictional connection with said fixed drum, a thrust bearing on said shaft, a spring retainer journaled for free rotation on said shaft between said free drum and thrust bearing, said spring retainer having one end in engagement with said thrust bearing and the other end guidedly connected to said free drum by rigid torque elements whereby the spring retainer is caused to rotate with said free drum while having capacity for relative axial movement with respect thereto, and spring means interposed between and carried by said spring retainer and said free drum for urging the latter towards the fixed drum.

3. In a hoisting apparatus, the combination with a power-driven shaft of two contiguous drums, one of said drums being fixed on said shaft and positively driven thereby and the other drum being free to rotate upon said shaft and having a frictional connection with said fixed drum, a thrust bearing on said shaft, a spring retainer journaled for free rotation on said shaft between said free drum and thrust bearing, said spring retainer having one end in engagement with said thrust bearing and the other end guidedly connected to said free drum by rigid torque elements whereby the spring retainer is caused to rotate with said free drum while having capacity for relative axial movement with respect thereto, and means at the end of said shaft for adjusting the position of said thrust bearing on said shaft to regulate the pressure exerted by said spring means.

4. In a hoisting apparatus, the combination with a power-driven shaft of two contiguous drums, one of said drums being fixed on said shaft and positively driven thereby and the other drum being free to rotate upon said shaft and having a frictional connection with said fixed drum, a thrust bearing on said shaft an annular spring retainer journaled for free rotation on said shaft between said free drum and thrust bearing, said spring retainer having one end in engagement with said thrust bearing and the other end guidedly connected to said free drum by rigid torque elements whereby the spring retainer is caused to rotate with said free drum while having capacity for relative axial movement with respect thereto, a telescoping housing for said spring retainer and thrust bearing, and spring means interposed between and carried by said spring retainer and said free drum within said telescopic housing for urging the free drum towards the fixed drum.

5. In a hoisting apparatus the combination with a power-driven shaft of two contiguous drums, one of said drum being fixed on said shaft and positively driven thereby and the other drum being free to rotate upon said shaft and having at one end a frictional connection with said fixed drum, and being longitudinally recessed at its

other end, a thrust bearing on said shaft, a spring retainer journaled for free rotation on said shaft between said free drum and thrust bearing, said spring retainer having one end in engagement with said thrust bearing and having its other end longitudinally recessed and guidedly connected to said free drum whereby the spring retainer is caused to rotate with said free drum while having capacity for relative axial movement with respect thereto, and spring means housed partially within the recesses of said spring retainer and partially within the recesses of said free drum for urging the free drum towards the fixed drum.

JULIUS TOROK.
